UNITED STATES PATENT OFFICE.

ARCHIBALD J. TURNER, OF CHICAGO, ILLINOIS, ASSIGNOR TO THOS. E. WILSON & CO.,
OF CHICAGO, ILLINOIS, A CORPORATION OF MAINE.

BASEBALL MITT.

Application filed March 25, 1925. Serial No. 18,078.

To all whom it may concern:

Be it known that I, ARCHIBALD J. TURNER, a citizen of the United States, and resident of Chicago, in the county of Cook and State of Illinois, have invented a certain new and useful Improvement in Baseball Mitts, of which the following is a full, clear, concise, and exact description, reference being had to the accompanying drawings, forming a part of this specification.

My invention relates to a mitt such as is used in playing baseball, and is particularly concerned with the provision of improved means for adjusting the hand insertion opening of such a mitt to suit the preference or requirements of any individual player.

Heretofore, adjustment of the hand insertion openings of baseball mitts has been accomplished by cross-lacing or by straps adapted to be secured by buckles, snap fasteners, or the like. These expedients for various reasons have not proven entirely satisfactory. They may be supplanted by the improvements of my present invention.

One of the objects of the present invention is to provide adjustment means which readily may be manipulated with one hand to effect the desired adjustment when the mitt is positioned upon the other hand of the player.

Another object of the invention is to provide adjustment means capable of a much greater number of adjustments than are the prior devices, secured by the conventional buckles or snap fasteners.

Another object of the invention is to provide adjustment means which need comprise no metal parts apt to injure a player or his clothing during playing,—as for instance in tagging a base runner.

Another object is to provide adjustment means which comprises no cross-laces, it being found that such laces have a tendency to become stretched or broken.

Another object of the invention is to provide adjustment means which presents a smooth surface of considerable area to the back of the hand or wrist of the player,—thereby being conducive to comfort.

Other objects of the invention will appear as the following description progresses.

In this specification and in the appended claims I have used the word "mitt" as a generic term covering and including all of the various gloves or mittens employed in

playing baseball or other games in which a mitt is required.

In the accompanying drawing illustrating my invention.

Figure 1 is an elevational view of the rear of a catcher's mitt to which the improvements of the present invention have been applied;

Figure 2 is a fragmentary sectional view which may be regarded as having been taken on the line 2—2 of Figure 1; and

Figure 3 is a fragmentary elevational view illustrating how the thongs of the adjustment strap may be tied together.

Similar characters of reference refer to similar parts throughout the several views.

The catcher's mitt shown in Figure 1 comprises the usual pad (not shown) which is enclosed in a suitable leather case or covering. This covering comprises a plurality of sheets or pieces of leather, only one of which is shown in the accompanying drawings, namely the rear portion of the cover illustrated at 5. The several elements of the cover may be secured together in any desired manner, as for instance by leather lacing indicated at 6. In this type of glove the inside of the hand of the wearer bears against the outer surface of the cover member 5 when the mitt is in use.

A receptacle for the hand and fingers of the player is provided by a plurality of pieces of leather indicated at 7—7 which are stitched to the cover member 5, and to each other, to provide pockets for the thumb and fingers and partially to cover the back of the hand.

The hand insertion opening into the pocket afforded by the several members 7—7 is indicated at 8, the material of the members 7—7 constituting the margins of the opening 8 preferably being turned outwardly to a certain extent and being provided with a binding bead of leather which is indicated at 9.

As thus far described, the mitt illustrated in the accompanying drawing need not differ essentially from other high grade mitts commonly employed in playing baseball. I shall now describe those features of improvement with which my invention is particularly concerned.

At 10 is illustrated a strap which has one end rigidly stitched, or otherwise suitably secured, to that one of the members 7 which

affords the receptacles for the thumb and forefinger, the strap preferably being attached to such member 7 at a point adjacent one of the lateral margins of the opening 8. A slit 11 is formed in said last mentioned member 7 at a point adjacent the contiguous lateral margin of the opening 8, the strap 10 being passed through this slit as is clearly illustrated in the drawing. The strap 10 extends across the hand insertion opening 8, that portion of the strap which lies between the lateral margins of the opening preferably being relatively wide and, if desired, being lined with leather reinforcement indicated at 12, such lining, if employed, preferably being held in position on the strap by suitable stitching as illustrated.

At its free end, i. e., the end which is not stitched or otherwise permanently secured 20 to the mitt, the strap 10 is bifurcated to provide a pair of integral thongs 13—13. These thongs extends through openings 14—14 which are formed in the material constituting the left (Fig. 1) margin of the opening 8. One of the openings 14 is provided for each thong and, if desired, each of the openings 14 may register with a similar opening formed in a piece of leather 15 which, it will be noted, is stitched to the outer surface of 25 that one of the members 7 which affords the pocket for the little finger and constitutes the left (Fig. 1) margin of the hand insertion opening. As will presently appear, the piece 15 cooperates with the last mentioned 30 member 7 to afford friction guides for the thongs 13—13.

Formed in the member 15 are two pairs of parallel slits, indicated at 16—16 and 40 17—17. Each of the thongs 13 is extended through both of the slits of one of these pairs, as is clearly illustrated in the drawings, and thus is adapted to be frictionally but yieldingly held between the member 15 and the one of the members 7 to which the said member 15 is attached. Therefore, the member 15 and the one of the members 7 to which it may be attached may be said to 45 cooperate to afford friction guides through which the thongs 13—13 are separately extended.

In using the adjustment means just described, the left hand of the player is inserted through the opening 8 and the thongs 13—13 are grasped with the right hand and 55 drawn through their friction guides until the desired adjustment of the strap 10 has been secured. The thongs are then tied together as is illustrated in Figure 3. If the mitt is one which is being used by several 60 players requiring different adjustments, the simple knot such as illustrated in Figure 3 will suffice, as little or no strain is thrown

upon the knot due to the action of the friction guides through which the thongs are extended. If the mitt is one which is 65 always used by the same player, the thongs may be tied with a double knot, in which case the superfluous material at the free ends of the thongs is preferably cut away.

Having thus illustrated a preferred embodiment of my invention, what I claim is new and desire to secure by Letters Patent in the United States is:

1. A mitt having a hand insertion opening, a strap secured to one lateral margin of the opening, extending across the opening, and having its other end bifurcated to provide a pair of thongs, together with a friction guide member associated with the other lateral margin of said opening affording 75 two pairs of slots through which said thongs are separately extended.

2. A mitt comprising a hand insertion opening provided with outwardly turned lateral margins, a strap having one end secured to the outer surface of the material of the mitt which bounds one of said lateral margins, said strap then extending through a slot in said material and across said opening and having its free end bifurcated to 80 provide a pair of thongs, slots in the material bounding the other lateral margin of said opening, said thongs passing through said slots, and a friction guide member between which and the material at the last 85 mentioned margin of the opening said thongs are passed, said guide member being provided with two pairs of slots through 90 which said thongs are separately extended.

3. A mitt having a hand insertion opening 100 and an adjustment strap having one end secured to one lateral margin of said opening, said adjustment strap extending substantially across the hand insertion opening and having its other end bifurcated to provide a pair of thongs, and frictional means associated with the other lateral margin of said opening affording guides through which 105 said thongs are separately extended.

4. A mitt having a hand insertion opening 110 and adjustment means attached to one of the lateral margins of said opening and comprising a pair of thongs, and frictional guiding means for said thongs associated with the other lateral margin of said opening, said frictional guiding means comprising two layers of flexible material between which said thongs are passed, one of said layers being provided with two pairs of slots through which said thongs are 115 separately extended.

In witness whereof, I hereunto subscribe my name this 23rd day of March, 1925.

ARCHIBALD J. TURNER.
